UNITED STATES PATENT OFFICE.

ROBERT F. CLEMENT, OF CHICAGO, ILLINOIS.

DESIGN FOR A PICTURE-FRAME.

• 50,058.

Specification for Design.

Patented Dec. 19, 1916.

Application filed November 2, 1916. Serial No. 129,240. Term of patent 3½ years.

To all whom it may concern:

Be it known that I, ROBERT F. CLEMENT, a citizen of the United States, residing at Chicago, in the county of Cook and State of Illinois, have invented a new, original, and ornamental Design for a Picture-Frame, of which the following is a specification, reference being had to the accompanying drawing, forming a part thereof.

The figure is a face elevation of a picture frame showing my new design.

I claim:

The ornamental design for a picture frame, as shown.

ROBERT F. CLEMENT.

Witnesses:

MILTON T. MILLER,
WM. NEVARRE CROMWELL.
